(57) **CLAIM**

An ornamental design for the moving indicator, as shown and described.

DESCRIPTION

FIG. 1 is a front view of my moving indicator showing my new design. Gaming machines are shown in dashed lines, and are not part of the claimed design;

FIG. 2 is a side view of the design of FIG. 1; and

FIG. 3 is a top view of the design of FIG. 1.

FIG. 4 is a front view of my moving indicator showing a first alternative design to FIG. 1. Gaming machines are shown in dashed lines and are not part of the claimed design;

FIG. 5 is a side view of the design of FIG. 4; and

FIG. 6 is a top view of the design of FIG. 4.

FIG. 7 is front view of my moving indicator showing a second alternative design to FIG. 1. Gaming machines are shown in dashed lines and are not part of the claimed design;

FIG. 8 is a side view of the design of FIG. 7; and,

FIG. 9 is a top view of the design of FIG. 7.
